UNITED STATES PATENT OFFICE.

ALLEN A. VAN ORSDALE, OF PHILADELPHIA, PENNSYLVANIA.

CONTAINER.

1,402,692.

Specification of Letters Patent.

Patented Jan. 3, 1922.

Application filed November 27, 1920. Serial No. 426,744.

To all whom it may concern:

Be it known that I, ALLEN A. VAN ORSDALE, a citizen of the United States, residing at Philadelphia, in the county of Philadelphia and State of Pennsylvania, have invented new and useful Improvements in Containers, of which the following is a specification.

This invention relates to containers and it has more particular reference to containers or cartridges for fluid, semi-fluid or plastic and semi-plastic substances.

The primary object of this invention is to provide a container or cartridge of the type referred to which is adapted for disposition in an enclosing or surrounding receptacle from which the content can be permitted to flow in regulated or other predetermined quantities.

Another object of the invention is to provide a container or cartridge of the class above specified which by its novel structure lends to increased cleanliness and better sanitation in that its content can be exhausted with the minimus of contact with the receptacle into which the said container or cartridge is inserted for the discharge of its contents.

A still further object of my invention is to provide a container or cartridge of the nature referred to which is characterized by the fact that when placed in position for use it can be automatically punctured to the requisite degree for effecting the discharge of its contents.

With the foregoing fundamental and other objects in view as will later on be more apparent my invention consists essentially of a tubular container which is adapted to be hermetically sealed when once filled, said container being formed at one or more points, part or parts with a section or sections of reduced thickness which rend readily when external pressure is exerted thereagainst but are of a nature to withstand the normal outward pressure of the filled container or cartridge.

In the further disclosure of the invention reference is to be had to the accompanying sheet of drawings constituting a part of this specification, and in which like characters of reference designate the same or corresponding parts in all the views.

Figure 1— is a central vertical section through a container or cartridge more par-

ticularly adapted for containing a fluid or liquid substance.

Figure 2— is a top plan of the same.

Figure 3— is an underside plan thereof.

Figure 4— is a central vertical section of a slightly modified form of the invention.

Figure 5— is a top plan of the same; and

Figure 6— is an under side plan thereof.

Referring to the drawings which illustrate the embodiment of my invention as more particularly adapted for containing fluid, liquid or similar substance or compositions of matter, the numeral 10 designates a cylindrical or tubular body having a bottom 11 and a top 12, the latter being hermetically sealed thereon after said body 10 has been filled with a liquid or fluid 13, such as lubricating oil for example.

Conveniently axially central of the bottom 11 I form a conical indent 14 of reduced thickness in cross section of the material, and radially projecting therefrom I form grooves or creasings 15 similarly of reduced thickness in cross section.

Integral with the top or cover 12 and centrally thereof I form a button or finger grip 16—Figures 1 and 2—which is preferably seated in a dished part 17 so that no protrusion exists beyond the plane of the outer upper face of said cover 12, whereby economy in space is effected when packing the containers or cartridges.

In some instances I may insert the top or cover 12 as shown by Figures 4 and 5, and in this case I prefer to provide a collapsible finger grip 18 of appropriate nature and dimensions, and it will be readily seen that in this instance compactness is also effected—the parts being shown somewhat exaggerated in order to ensure a clear conception of the invention.

In use, and assuming that the container or cartridge 10 is filled with a fluid or liquid—such as a lubricating oil—and that said container or cartridge is adapted for insertion into a lubricator cup having an upstanding conical projection over the discharge orifice it will be readily seen that said projection will pierce the conical indent 14 and that by virtue of the radially projecting grooves or creasings 15 an easy and even rent will result whereby the content of the container or cartridge is discharged.

Furthermore, it will be readily seen that the provision of the button 16 or finger grip

18 serves as an easy means for withdrawing the container or cartridge 10 when empty, as well as aiding in its insertion into whatsoever receptacle said container is adapted for. 5 Still further it is to be noted that by providing the button or finger grip axially in line with the conical indent 14 a slight downward pressure thereon will materially aid in the puncturing of said container when 10 the latter are full as prior to use. Whilst I have referred to one particular application of my invention it is to be clearly understood that I do not restrict myself in any way to its use or to the material from 15 which the container or cartridge 10 is made providing it be of a nature and texture which lends itself readily to formation in the manner set forth, and by the use of which a serviceable article is produced, the 20 indent 14 and creasings or grooves 15 of reduced thickness only serving to effect the easy production of a discharge outlet and in no way materially reducing the strength of the surrounding parts when the container 25 or cartridge is full. Obviously cartridges or containers of the nature described may be employed in numerous ways, for example as containers for liquid soap, cleansing fluid, or as containers for any other fluid, liquid, 30 plastic or semi-plastic substances to be dispensed in predetermined quantities, and it will be self-evident that by my invention I provide a sanitary and extremely useful article for the purposes briefly referred to. 35 Finally, I wish it understood that whilst there has been shown and described the best known embodiment of this invention it is to be clearly understood that I do not limit myself in any way to the shape or pattern set 40 forth but deem myself at liberty to make such changes therein as reasonably fall within the scope of the appended claims.

Having described my invention what I claim as new and desire to secure by Letters 45 Patent is:—

1. As a new article of manufacture, a holder for fluid substance consisting of a cylindrical container having a closed-in and an opposed sealable end, said closed-in end having a centrally disposed indent and 50 grooves of reduced thickness in cross-section radiating therefrom so that when a fixed resistance is encountered by said indent a puncturing of the closed-in end results.

2. As a new article of manufacture, a 55 holder for fluid substance consisting of a cylindrical container having a closed-in and and opposed sealable end, said closed-in end having a centrally disposed indent and grooves of reduced thickness in cross-section 60 radiating therefrom so that when a fixed resistance is encountered by said indent a puncturing of the closed-in end results, and a finger-hold axially central of the sealable 65 end.

3. As a new article of manufacture, a holder for fluid substance consisting of a cylindrical container having a closed-in and an opposed sealable end, said closed-in end having a centrally disposed indent and 70 grooves of reduced thickness in cross-section radiating therefrom so that when a fixed resistance is encountered by said indent a puncturing of the closed-in end results, and an inset finger-hold axially central of the 75 outer face of the sealable end.

4. As a new article of manufacture, a holder for fluid substance consisting of a cylindrical container having a closed-in and an opposed sealable end, said closed-in end 80 having a centrally disposed indent and grooves of reduced thickness in cross-section radiating therefrom so that when a fixed resistance is encountered by said indent a puncturing of the closed-in end results, and 85 a collapsible inset finger-hold axially central of the outer face of the sealable end.

In testimony whereof I affix my signature.

ALLEN A. VAN ORSDALE.
